UNITED STATES PATENT OFFICE.

EVERETT B. CUSHMAN, OF TOPEKA, KANSAS, ASSIGNOR TO THE PIERSEN MANUFACTURING COMPANY, OF TOPEKA, KANSAS, A CORPORATION OF KANSAS.

AUTOMATIC OIL-FEED.

1,375,748.

Specification of Letters Patent. Patented Apr. 26, 1921.

Application filed May 21, 1919. Serial No. 298,633.

To all whom it may concern:

Be it known that I, EVERETT B. CUSHMAN, a citizen of the United States, residing at Topeka, in the county of Shawnee and State 5 of Kansas, have invented certain new and useful Improvements in Automatic Oil-Feeds; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to lubricating systems for motors and it particularly contemplates the provision of means for maintaining a constant supply of lubricating oil in the crank case of a motor.

20 One of the objects of my invention is to provide a simple and easily operated means for maintaining the oil level in the crank case of an explosion motor constant, this being an important feature where the splash system 25 of lubrication is employed, and it is also the object of my invention to provide means whereby the level of the oil in a container for augmenting the main supply, may be observed.

30 In the drawings,

Figure I is a vertical longitudinal sectional view through a mechanism constructed in accordance with my invention, and

Fig. II is a sectional view on the line 35 II-II of Fig. I.

The crank case 1 may be of any approved construction to receive the crank 2 to which may be connected any number of connecting rods 3, one for each piston of the motor, as 40 will be well understood. The crank case is shown in communication with a float chamber 4 through an opening 5, formed by a diaphragm 6 that separates the upper portion of the float chamber from the interior of the crank case and serves as a baffle to prevent actuation of the float upon agitation of the oil by the crank.

45 The top of the float chamber also comprises the bottom of a cup 7 that supports 50 a container 8 from which the supply of oil

to the crank case is augmented through a port 9, when the valve 9' is lifted by the heel 10 of the float 11 that is pivoted in the float chamber and rises and falls with the rise and fall of oil in the crank case. The container 55 8 preferably consists of an inverted glass jar, of the well known "Mason" type, the neck 12 of which is threaded into the collar 13 of the cup 7.

In the bottom of the cup 7 is an orifice 60 14 through which the container communicates with a filling chamber 15, cast integral with the float chamber and container cup. Supported on and communicating with the filling chamber is a tube 16, which preferably rises parallel with the container and has a removable cap 17. Located within the container 8 is a tube 18, the lower end of which is threaded into the bottom of the cup and extends therethrough to atmosphere 70 at one side of the float chamber and the upper end of which terminates above the oil level in the container, so that when the container is being filled, air may escape through the tube as oil enters through the orifice 15, 75 and so that discharge through the valved port 9 to the float chamber and crank case may be assisted by atmospheric pressure.

When the parts are assembled as indicated in Fig. I and the oil level in the crank case 80 falls below normal, there will be a drop of the float valve 11 causing the end 10 thereof to unseat the valve 9' and permit oil to flow through the port 9 into the float chamber and through the inlet opening 5 to the crank case 85 until the level of the oil is restored to normal, whereupon the float will have risen sufficiently to permit the valve 9' to become seated and cut off the supply.

As the crank splashes through the body of oil in the crank case, there will be more or less agitation in the body of oil but this agitation will not be communicated to the oil in the float chamber to any appreciable degree because the baffle 6 serves as a wall to effectually separate the two chambers while the opening 5 constituting an inlet port, permits the normal level of the oil in the float chamber and the crank case to remain uniform. Any suitable means may be provided for 100

- 5 pivoting the float lever in the chamber 4 but I prefer to construct the float lever with trunnions 19 and 20 and support them by point bearings 21 and 22 to assist in rendering the valve actuator or float sensitive in operation and to prevent the float lever from sticking or operating sluggishly in the event that the requirement for opening the valve 9' occurs only between long intervals.
- 10 6 The device may consist principally of a casting easily fastened to the crank case in the form of a bracket by means of the fastening devices 23 and 24.
- 15 7 While the construction which permits a Mason or similar jar to be used as a container for holding the augmenting supply of oil is an important feature of my invention, I do not wish to be limited to the employment of such a jar for while the jar serves the dual 80 purpose of a container and sight tube and materially assists in reducing the cost of manufacture of the device, the valve mechanism and filling means will operate efficiently with other forms of containers.
- 20 8 25 9 What I claim and desire to secure by Letters Patent is:
1. An automatic oil feed comprising a float chamber, an inverted glass jar located above the chamber, means separating the jar and float chamber comprising a port, a valve controlling the port, a float in the float chamber controlling the valve, and a tube leading from the top of the jar to atmosphere.
  2. An automatic oil feed comprising a float chamber, a cup above the float chamber, having a port, an inverted glass jar carried by the cup, a valve controlling said port, a float in the float chamber controlling the valve, and a filling chamber, the bottom of the cup having communication with the filling chamber and the top of the container having communication with atmosphere, for the purpose set forth.
  3. In a device of the class described, a float chamber adapted to communicate with the crank case of a motor, a cup above the float chamber and having a port communicating therewith, a valve controlling said port, a float in the float chamber for actuating the valve, an inverted container carried by the cup, a tube in the floor of the cup communicating with atmosphere at one end and with the inverted container at the other end, and means for supplying oil to the inverted container.
  4. In a device of the class described, a float chamber adapted to communicate with the crank case of a motor, a container above the float chamber, a valved partition separating the container from the float chamber, a float in the float chamber for actuating the valve in the partition, and a tube projecting through the partition and commun-

cating with atmosphere at one end and with the container at the other.

5. In a device of the class described, a float chamber adapted to communicate with the crank case of a motor, a container above the float chamber, a valved partition separating the chamber from the float chamber, a float in the float chamber for actuating the valve in the partition, a tube projecting through the partition and communicating with atmosphere at one end and with the container at the other, and a feed tube in open communication with the container and adapted for supplying oil thereto.

6. In combination with a crank case, a float chamber communicating therewith, a depending baffle extending from the top of the float chamber to a point just above the floor thereof, a container above the float chamber, a partition normally closing communication between the container and the float chamber, a valve in said partition, a float for actuating the valve, and a filling member in constant communication with the container, comprising a tube co-extensive vertically with the container.

7. In a device of the class described, a float chamber adapted to discharge into the crank case of a motor, a recessed member above the float chamber and having an orifice communicating therewith, a removable, inverted glass jar received in the recessed member, a float, and a float-actuated valve in the orifice for controlling the discharge of oil from the container into the float chamber.

8. In a device of the class described, a float chamber adapted to discharge into the crank case of a motor, a recessed member above the float chamber and having an orifice communicating therewith, a removable, inverted glass jar received in the recessed member, a float, a float-actuated valve in the orifice for controlling the discharge of oil from the container into the float chamber, and a filling chamber in constant communication with the jar through an opening in the floor of the recessed member.

9. In a device of the class described, a float chamber adapted to communicate with the crank case of a motor, a threaded recessed member above the float chamber and having a valved orifice communicating therewith, a float in the float chamber for actuating the valve, an inverted glass jar engaging the threaded recessed member, a tube in the floor of the recessed member and communicating with atmosphere at one end and with the glass jar at the other end, and means for supplying oil to the jar.

10. In an automatic oil feed for internal combustion engines, the combination of a float chamber adapted to discharge into the crank case of an engine, a removable in-

verted receptacle connected to said float chamber, a gravity seated valve controlling the supply of liquid from the removable receptacle to said float chamber, and a float 5 for unseating said valve.

11. In an automatic oil feed comprising a float chamber, an inverted glass jar located

above the chamber, means separating the jar and float chamber comprising a port, a normally seated valve controlling the port, 10 and a float in the float chamber for unseating said valve.

In testimony whereof I affix my signature.

EVERETT B. CUSHMAN.
